UNITED STATES PATENT OFFICE.

JULIUS KRAFT, OF PHILADELPHIA, PENNSYLVANIA.

CUSHIONED CAP.

1,315,313.

Specification of Letters Patent.

Patented Sept. 9, 1919.

Application filed October 5, 1916. Serial No. 123,948.

To all whom it may concern:

Be it known that I, JULIUS KRAFT, a citizen of Switzerland, residing at Philadelphia, in the county of Philadelphia and State of Pennsylvania, have invented certain new and useful Improvements in Cushioned Caps, of which the following is a specification.

This invention relates to apparel caps and while the cap embodying the present invention is particularly designed for use by travelers, nevertheless, it may be used to great advantage by sportsmen, automobilists, and in fact, by anyone who for business or pleasure is required to travel or be so situated as to be deprived of the use of a bed or similar place of rest for any considerable length of time. It is the primary aim of the invention to provide a cap which will not differ materially in its appearance from the ordinary cap worn by travelers and sportsmen and which will yet be so constructed as to constitute a cushion for either the back or the sides of the head when the head is rested against a car window frame or other object depending, of course, upon the circumstances upon which the cap is worn and which object would otherwise prove so uncomfortable as to prevent one obtaining the desired rest. While it has been proposed to provide a cap or other head covering with an inflatable cushion member, it has been found that this is undesirable for the reason that in order to secure the advantages which might be expected to flow from a head covering so constructed, it is necessary to inflate the pneumatic cushion and after use, to deflate the same. Furthermore, the cushion must be of considerable size or in other words, must bulge outwardly from the head a considerable distance in order to obtain the desired cushioning effect and the head covering is therefore rendered unsightly and clumsy in appearance. The present invention, therefore, has as a further aim to provide a cap or other type of head covering with a cushioning medium, the presence of which will not be noticeable to such an extent as to render the head covering bulky or unsightly in appearance.

In the accompanying drawings,

Figure 1 is a view illustrating the cap embodying the present invention in side elevation,

Fig. 2 is a view illustrating the cap in front to rear section.

In the drawings, the numeral 1 indicates in general, a cap of substantially the ordinary shape provided with a lining 2 and at its front with a vizor 3. The cap, at the rear and at each side, is provided with a padding which constitutes the cushioning medium for the cap and in order to provide a pocket for the padding, the cap is preferably formed at its rear and at each side 65 larger than it would be if it were not for the presence of the said pocket and the padding filling the same, and by reference to Fig. 2, it will be observed that the lining 2 forms the inner wall of this padding and 70 this lining may be of such area as to extend within the back and sides of the cap to form the pocket or it may be extended within the top at the forward side of the cap as shown in the present drawings. In 75 any event, that portion of the lining which forms the inner wall of the pocket is indicated by the numeral 4 and the portion of the material of the cap which forms the outer wall of the pocket is indicated in general by the numeral 5. At the rear and sides of the cap, the lower edge of the lining 5 and the cloth of the cap proper are united by a seam as indicated at 6 which seam closes the lower side of the pocket and the 80 upper side of the said pocket is closed by a line of stitching as indicated at 7. The line of stitching 6 extends continuously along the lower edges of the cloth of the cap and the lining therefor from the ends 85 of the vizor 3 and the line of stitching 7 extends from the said ends of the vizor continuously around the rear side of the top of the cap and approximately in a horizontal plane. A line of loose stitching 8 90 is passed through the lining and the material of the cap and extends from points slightly in the rear of the ends of the line of stitching 7 and upon the line of stitching 6 continuously around the rear side of the 95 cap. Another line of loose stitching 9 extends from the line of stitching 6 at points in rear of the line of stitching 8 also continuously around the rear side of the cap and below the said line of stitching 8. Thus 100 all of the lines of stitching 6, 7, 8 and 9 converge in the general direction of the forward side of the cap. By reference to Fig. 2, it will be observed that the lining or more specifically, the portion 4 thereof 110 which forms the inner wall of the pocket will, when the cap is applied to the head,

more or less snugly fit the sides of the head and it will further be observed at this point that the lower edge of the cap at the sides of the head extends down to the ears and that at the rear side of the cap, the said lower edge is considerably lower than in the ordinary cap.

The pocket is provided with a filling or padding 10 which may be of any suitable material such for example, as hair or wool and it will be observed that the lines of stitching 8 and 9 pass through this filling and consequently tend to prevent displacement of the filling within the pocket. Referring now particularly to Fig. 2, it will be observed that the filling 10 is so arranged within the pocket that the cushion will be of maximum thickness between the lines of stitching 8 and 9 although it decreases in thickness toward the sides and front of the cap. In other words, the thickness of the cushion decreases as the lines of stitching 8 and 9 converge. It will also be observed that the cushion decreases in thickness from the stitching 8 toward the line of stitching 7 and from the line of stitching 9 gradually toward the line of stitching 6. As stated, the lines of stitching 8 and 9 serve to prevent disarrangement of the filling 10 and consequently, the filling will not be liable to become bunched at any one point after the cap has been in use for a considerable length of time.

In the use of the cap, the head may be

rested against the back of the car seat or 35 either side of the head may be rested against the window frame of the car assuming that the cap is being worn by a traveler, or under other conditions of use, the head may be rested at the back or at either side against any 40 convenient object and all shocks will be cushioned and absorbed by the filling 10 and the wearer of the cap will be permitted to rest comfortably. If desired, other lines of stitching may be passed through the walls 45 of the pocket and through the filling 10 although I have found it quite sufficient to provide the lines of stitching 8 and 9 for the purpose above stated.

Having thus described my invention, 50 what is claimed as new is:

A head covering having its lower rear and side edges located considerably below the crown line of the covering, the said covering between its said edges and a line extending at the rear and sides of the covering above the crown line of the covering, being provided with a cushion consisting of a permanent filling, the said cushion being of maximum thickness at the rear of the 60 cover and gradually decreasing in thickness toward the said lower rear and side edges of the covering and toward the said line, the cushion being also gradually decreased in thickness from the rear of the covering to 65 ward the sides thereof.

In testimony whereof I affix my signature.
JULIUS KRAFT. [L.S.]
